(57) CLAIM

The ornamental design for a stick product such as perfume, deodorant or lipcolor, as shown and described.

DESCRIPTION

FIG. 1 is a front perspective view of the stick product such as perfume, deodorant or lipcolor showing my new design;
FIG. 2 is a top plan view of the design illustrated in FIG. 1;
FIG. 3 is a left side elevation view of the design illustrated in FIG. 1;

FIG. 4 is a front elevation view of the design illustrated in FIG. 1; and,

FIG. 5 is a rear elevation view of the lipstick design illustrated in FIG. 1.

The structures shown in broken lines are for illustrative purposes only and form no part of the claimed design.
